Crimsoo, Inc., Kansas City, Mo., a corporation
of Missouri

Application August 31, 1953, Serial No. 26,639

Term of patent 14 years

(Cl. D14—3)

To all whom it may concern:

Be it known that we, Thomas E. Oakes, a citizen of the United States, residing at Prairie Village, in the county of Johnson and State of Kansas, and Daniel S. Truog, a citizen of the United States, residing at Kansas City, in the county of Jackson and State of Missouri, have invented a new, original, and ornamental Design for a Conveyer Cabinet for Transporting Hot and Cold Foods, of which the following is a specification, reference being given to the accompanying drawings forming a part thereof.

Fig. 1 is a front perspective view of a conveyer cabinet for transporting hot and cold foods, showing our new design and looking at one end thereof.

Fig. 2 is a front perspective view thereof in partially open position.

The rear and other side of the conveyer cabinet are plain.

We claim:

The ornamental design for a conveyer cabinet for transporting hot and cold foods, as shown and described.
